UNITED STATES PATENT OFFICE.

JOSEPH MUSER, OF NEW YORK, N. Y.

PNEUMATIC DOOR-CHECK.

SPECIFICATION forming part of Letters Patent No. 392,927, dated November 13, 1888.

Application filed April 5, 1888. Serial No. 269,732. (Model.)

To all whom it may concern:

Be it known that I, JOSEPH MUSER, of the city, county, and State of New York, have invented certain new and useful Improvements 5 in Door-Checks, of which the following is a specification.

This invention relates to an improved pneumatic door-check of that class in which the motion of the door in closing is gradually arrested by the joint action of a piston applied to the door-frame and a valved air-cylinder applied to the door.

The invention consists in the construction and combination of parts and details, as will 15 be fully described and set forth hereinafter, and pointed out in the claims.

In the accompanying drawings, Figure 1 represents a front elevation of a door with my improved pneumatic door-check, showing the 20 same in closed position. Fig. 2 is a vertical transverse section of the door-frame on line $x-x$, Fig. 1, showing an end elevation of the air-cylinder of my improved door-check. Figs. 3 and 4 are horizontal sections on line $y-y$, Fig. 25 1, showing the door and its check device respectively in closed and open position; and Fig. 5 is a vertical transverse section on line $z-z$, Fig. 3.

Similar letters of reference indicate corresponding parts.

Referring to the drawings, A represents a door; B, the door-frame; C, a piston, the piston-rod C' of which is applied by a suitable hinge-connection to the door-frame, and D an air-cylinder that is supported on a bracket, D', which bracket is hinged to the door, as shown clearly in Fig. 1. The piston C is supported at a proper angle of inclination for the air-cylinder D, either in fixed position or by means 35 of a set-screw, a, and a spring, b, which latter is interposed between lugs of the supporting-plate of the piston-rod C' and of a shoulder-plate, b', of the piston-rod, as shown clearly in Fig. 4. The air-cylinder D is open at that 40 side which faces the piston C, and provided at the opposite end with air-inlet openings d and with an interior suction-valve, d', of rubber, leather, or other suitable material, (shown in dotted lines in Fig. 1,) which valve opens so 45 as to admit air into the cylinder when the door is opened, but which is closed by the pressure of the air as soon as the open end of

the cylinder passes over the piston C. The cylinder D is further provided at its valved end with a small air-exhaust aperture, e, through 55 which the air compressed in the cylinder by the piston escapes slowly as the cylinder passes over the piston, so that the door is checked by the pneumatic action of the compressed air in the piston and prevented from closing too 60 quickly and noisily.

To the air-cylinder D is pivoted a connecting-rod, E, the opposite end of which is pivoted to a bracket-arm, E', which is adjustably guided in a bracket, E'', attached to the door-frame, the end of said bracket-arm extending into a socket, e', of the door-frame, as shown clearly in Figs. 3 and 4. The bracket-arm E' has to be made adjustable for the purpose of setting the connecting-rod E at the proper 70 distance from the door-frame, according to the style of hinge used. For closing the door automatically a spring-actuated closing device is employed, which consists of a barrel, F, applied to the door, a pintle, F', in said barrel, 75 and a spiral spring, F'', which is applied to the barrel and pintle in the usual manner for adjusting properly the tension of the spring. The pintle F' is connected by an arm, F³, at its upper end with an arm, F⁴, that is pivoted to 80 the arm F³ and to fixed ears of the door-frame, as shown clearly in Figs. 1 and 5.

The closing device forms no part of my invention, as the same is well known and has been used in connection with door-checks heretofore, the new feature of my door-check being the hinge-connection of the same by the pivot-rod with the adjustable bracket-arm of the door-frame, so that the cylinder is swung by the opening of the door from a position at an 90 angle thereto into a position parallel to the door, as shown in Fig. 4, and from the latter position into its normal position when the door is closed. By thus arranging the cylinder so as to swing this bracket on a hinge of 95 the door the air-cylinder is not in the way of the wall when the door is entirely opened, so that my improved pneumatic door-check can be applied to the door without interfering with the wall, as the fixed projecting cylinder of 100 the door-checks heretofore in use.

Having thus described my invention, I claim as new and desire to secure by Letters Patent—
1. The combination, with a door having an

air-cylinder open at one end and pivotally connected with said door and a pivot-rod connecting the door-easing with said air-cylinder, of a removable piston secured on the door-easing and fitting in the cylinder, a screw for adjusting the inclination of said piston, and a spring acting on the door, substantially as set forth.

2. The combination, with a door, of an air-cylinder connected pivotally with the same, a bracket applied to the door-easing, a bracket-

arm secured to said bracket, a pivot-rod connecting the bracket-arm with the air-cylinder, and a removable piston on the door-easing, substantially as set forth.

In testimony that I claim the foregoing as my invention I have signed my name in presence of two subscribing witnesses.

JOSEPH MUSER.
